THOMAS G. LUCAS, OF MIDDLETOWN, CONNECTICUT.

Letters Patent No. 96,819, dated November 16, 1869.

IMPROVEMENT IN FLASKS FOR MOULDING.

The Schedule referred to in these Letters Patent and making part of the same.

To all whom it may concern:

Be it known that I, THOMAS G. LUCAS, of Middletown, in the county of Middlesex, and State of Connecticut, have invented a new and useful Improvement in Foundry-Moulding; and I do hereby declare that the following is a full, clear, and exact description thereof, which will enable others skilled in the art to make and use the same, reference being had to the accompanying drawings, forming part of this specification.

This invention relates to a new and useful improvement in the manner of moulding patterns for making castings of iron, or other metal, and consists in the use of a draught-plate, (one or more,) in combination with the pattern, as hereinafter more fully described.

In the accompanying drawing—

Figure 1 represents a central longitudinal vertical section of the flask, the pattern on its match-plate and two draught-plates arranged as they are placed in the mould or flask.

Figure 2 is a view of the draught-plate.

Figure 3 is a vertical cross-section of fig. 1, through the line *x x*.

Similar letters of reference indicate corresponding parts.

The object of this invention is to prevent the breaking of the sand at the corners or angles of the mould in taking off the cope of the flask, (from the pattern,) and in drawing the pattern from the mould.

This I accomplish by means of one or more draught-plates, made of metal, or any other suitable material, which plates are made to accurately fit the pattern.

In this example of my invention, I apply the improvement to the moulding of a pump-cylinder, the pattern of which is marked A, in the drawing; but the improvement is applicable to other descriptions of castings—in fact it is applicable to almost every description of iron, brass, or other metal castings, as the draught-plates may be made to conform to the shape of almost any pattern, whether presenting a plain level surface at the parting of the pattern or not.

B represents the lower part or "nowel" of the flask. C is the "cope."

The pattern A is attached to a match or card-plate, *d*, one-half of the pattern being on each side. The use of the match-plate is common in moulding.

When the pattern has been rammed, or properly embedded in the sand, the cope is lifted off, leaving the pattern and match-plate in their former position.

The match-plate and pattern are then raised from the lower portion of the flask, the cope is replaced, or the flask is "closed," and the mould is complete; this, of course, after the "core" has been placed, and the "gating" from the sprue finished.

So far as we have described, we have not brought our improvement into use, but in taking the cope off the

pattern, and in taking or "drawing" the pattern from the "nowel," or lower portion of the flask, a difficulty has been experienced which our improvement is designed to remedy, and which it does remedy completely. The difficulty is, the breaking of the sand at the angles and corners, when such angles and corners are raised from the pattern, in lifting the "cope," and also when the pattern is raised from such angles in being drawn from the "nowel."

There is a certain amount of adhesion of the sand to the pattern which the most skilful moulder cannot wholly prevent, which adhesion, or the unsteady handling of the "cope" and pattern, or both combined, occasions these breaks.

The time occupied by the workman in mending (with "trowel" and "slick," or with his finger) these breaks, is frequently equal to all the rest of the labor performed in making the mould. The extent of the difficulty is in proportion to the skill of the workman, and is a very serious one with the most skilful.

As a means of lessening the evil, the moulder is compelled to use his sand in a very damp state, which in almost every description of moulding injuriously affects the casting. By the use of the draught-plates, the sand may be used comparatively dry, while its breaking at the corners is rendered simply impossible.

To accomplish this, we use one or more draught-plates E, which are (in outline) of the form and size of the flask, but with ends projecting, as seen in fig. 1, so that they, or either of them, may be lifted either with the cope or with the patterns.

The match-plate *d* projects in the same manner, and for the purpose of drawing the pattern.

The plate E is made to perfectly fit the pattern, as the space or opening F, fig. 2, will fit the centre of the pattern A.

The pattern is made in two halves, separated by the match-plate, as seen in the drawing. Now, to the flat side of each half is added just the thickness of the draught-plate E.

As seen in fig. 1, the parts of the flask are separated by the thickness of all three of the plates, but the flat side of each half of the pattern corresponds in position with the closing surfaces of the flask, so that when the plates are removed, the parts of the flask will close together with just half the mould of the cylinder in each.

With the plates on each part of the pattern, as seen in the drawing, (figs. 1 and 3,) and the parts of the flask filled with moulding-sand, rammed around the pattern, the moulder, in taking off his cope, will at the same time raise the upper draught-plate E. This plate as before stated, accurately fits the upper half of the pattern, and as it is raised, it necessarily lifts the sand clean from it, leaving nothing to be done in the way of mending.

The next operation is to draw the pattern with the

match-plate *d*. The lower draught-plate (accurately fitting the pattern) rests upon the sand in the "nowel," and remains there while the match-plate and pattern drawn, keeping the sand exactly to its place during operation. This draught-plate is then withdrawn, and the cope replaced, and the mould is completed, as before stated.

The match-plate, with the pattern, and also the draught-plates, are guided to and kept in their proper position in the flask by the dowel or steady-pins, which are attached to the nowel, as seen in fig. 3.

It may not be necessary to use more than one of these draught-plates in certain cases, nor is it required to use either in connection with a match or card-plate exclusively. I do not, therefore, confine myself to any particular method of using the draught-plate, nor for any particular description of casting, but design it for moulds for castings of every description to which it may be made applicable.

For the purpose of furnishing a further illustration of the use of the draught-plate when employed singly, and to show its adaptation to patterns which do not part in the middle, we will introduce the drawing, sheet 2, where the single draught-plate is seen without a match-plate, and with the pattern in a single piece.

Figure 1 is a longitudinal vertical section;

Figure 2 is a vertical cross-section; and

Figure 3 is a view of the draught-plate attached.

Similar letters of reference indicate corresponding parts in both sheets of drawing.

In dispensing with the match-plate, for supporting the pattern, as heretofore described, the pattern may

be extended at the ends, so that it will rest on the ends of the flask, there being recesses or slots in the flask to receive such projections.

These projections may extend through the flask, and serve as handles for drawing the pattern, but in moulding the pattern, either in one or two parts, without the match-plate, this arrangement is not indispensable.

It will be seen that the thickness of the draught-plate *E* is added to the centre of the pattern, as described above.

In taking off the cope, the plate is lifted with it, raising the sand clean from the pattern. When this is done, the plate is replaced over the pattern, and then the pattern is drawn through the plate, while the plate keeps the sand to its place, as before described. The plate is then lifted from the sand, and the cope is replaced, and the mould is complete, as stated above.

By replacing the draught-plate over the pattern, after the cope has been removed, all the advantages of two draught-plates are gained, with but a slight addition to the labor, while the expense is somewhat diminished.

Having thus described my invention, I claim as new, and desire to secure by Letters Patent—

The mould, composed of the parts *B* *C*, and plates *E* *d*, constructed and arranged as described.

THOS. G. LUCAS.
